US00D852416S

(12) **United States Design Patent** (10) **Patent No.:** **US D852,416 S**
(45) **Date of Patent:** **** Jun. 25, 2019**

(54) **HAIR STYLING AND HAIR CARE APPARATUS**

(71) Applicant: **Dyson Technology Limited**, Wiltshire (GB)

(72) Inventors: **Robert Mark Brett Coulton**, Bristol (GB); **Daniel John Thompson**, Bristol (GB); **Christopher Daniel Currer Wilkinson**, Swindon (GB); **Andrea Ee-Va Lim**, Bristol (GB); **Peter David Gammack**, Gloucester (GB); **Stephen Benjamin Courtney**, Gloucester (GB); **Alexander Stuart Knox**, Swindon (GB); **Jeremy Adam Tomas Ellis-Gray**, Dursley (GB); **Nicholas Giles Wilkins**, Gloucester (GB); **Jonathan James Harvey Heffer**, Swindon (GB); **Annmarie Rita Nicolson**, Bristol (GB); **Emma Victoria Carson**, Swindon (GB); **Wei Yi Chia**, Singapore (SG); **Wei Jie Lam**, Singapore (SG)

(73) Assignee: **Dyson Technology Limited**, Malmesbury, Wiltshire (GB)

(**) Term: **15 Years**

(21) Appl. No.: **29/627,773**

(22) Filed: **Nov. 29, 2017**

(30) **Foreign Application Priority Data**

May 30, 2017 (EM) 004023927-0001

(51) LOC (11) Cl. **28-03**

(52) U.S. Cl.

USPC **D28/18**

(57) **CLAIM**

We claim the ornamental design for a hair styling and hair care apparatus, as shown and described.

DESCRIPTION

FIG. 1 is a top perspective view of a hair styling and hair care apparatus showing our new design;

FIG. 2 is a bottom perspective view thereof;

FIG. 3 is a side view thereof;

FIG. 4 is a top view thereof;

FIG. 5 is a bottom view thereof;

FIG. 6 is a front view thereof; and,

FIG. 7 is a rear view thereof.

The view opposite the side view of FIG. 3 is a mirror image thereof, and therefore, is omitted.

1 Claim, 7 Drawing Sheets
